Primary Examiner — Terry A Wallace(74) *Attorney, Agent, or Firm* — CreatiVenture Law, LLC; Dennis J M Donahue, III(57) **CLAIM**

The ornamental design for a locking cooler, as shown and described.

DESCRIPTION

FIG. 1 is a front perspective view of a locking cooler;

FIG. 2 is a back perspective view thereof;

FIG. 3 is a front view thereof;

FIG. 4 is a back view thereof;

FIG. 5 is a top view thereof;

FIG. 6 is a bottom view thereof;

FIG. 7 is a left side view thereof; and,

FIG. 8 is a right side view thereof.

The broken lines represent sections of the locking cooler that form no part of the claimed design.

1 Claim, 4 Drawing Sheets(56)
